UNITED STATES PATENT OFFICE.

JOSEPH O. FISHER, OF THE UNITED STATES NAVY.

METHOD OF AND APPARATUS FOR INJECTING FUEL INTO COMBUSTION-CHAMBERS.

1,252,254.

Specification of Letters Patent. Patented Jan. 1, 1918.

Application filed July 10, 1917. Serial No. 178,778.

To all whom it may concern:

Be it known that I, JOSEPH O. FISHER, a lieutenant-commander in the United States Navy, and a citizen of the United States, 5 residing at Washington, in the District of Columbia, have invented certain new and useful Improvements in Methods of and Apparatus for Injecting Fuel into Combustion-Chambers; and I do hereby declare the following to be a full, clear, and exact description of the invention, such as will enable others skilled in the art to which it appertains to make and use the same.

This invention relates to a method of and 15 an apparatus for injecting fuel into internal combustion engines, and has for its object to improve the methods and means heretofore proposed.

With this and other objects in view the invention consists in the novel steps and combinations of steps constituting the method, and in the novel parts and combinations of parts constituting the apparatus, all as will be more fully hereinafter disclosed and particularly pointed out in the claims.

Referring to the accompanying drawings, forming a part of this specification, in which like numerals designate like parts in all the views:—

30 Figure 1 is a longitudinal sectional view of an injector made in accordance with this invention;

Fig. 2 is a diagrammatic view of a modified form of the invention;

35 Fig. 3 is an enlarged detail sectional view of the lower portion of the injector, taken on the line 3—3 of Fig. 6;

Fig. 4 is a sectional view taken on the line 4—4 of Fig. 3 looking in the direction of 40 the arrows;

Fig. 5 is a sectional view taken on the line 5—5 of Fig. 3 looking in the direction of the arrows;

Fig. 6 is a view similar to Fig. 5 taken on 45 the line 6—6 of Fig. 3 looking in the direction of the arrows;

Fig. 7 is a diagrammatic view of a circulating system that may be employed in this invention;

50 Fig. 8 is a sectional view of a somewhat modified form of injecting nozzle; and

Fig. 9 is a diagrammatic view of a modified form of circulating system capable of employing the nozzle shown in Fig. 8.

55 1 indicates any suitable engine, 2 a water jacket therefor, 3 the interior of an engine

cylinder 8, 4 a port leading into said cylinder, 5 a plug carrying the port 4, 6 a circular chamber carried by the plug 5, and 7 a plurality of inclined ports or passages 60 also carried by said plug, and tangentially entering said chamber as shown. The plug 5 fits the cylinder 8, and is screw threaded into the injector nozzle or body 10 as at 9. Said nozzle 10 is provided with the inlet passage 11 leading into the annular chamber 12 with which the passages 7 also communicate, as shown.

Said nozzle 10 is hollow or bored out, as illustrated, to accommodate the sleeve 13, 70 and inside said sleeve is located the hollow bushing or plug 14. Said sleeve 13 is split, or cutaway, on one side to provide the exit passage 15 communicating with the annular chamber 16 preferably located at the upper 75 end of the plug 5.

The port 4 is controlled by the valve member 20, provided with the tapered or cone-shaped portion 21 fitting the lower portion of the chamber 6, and also provided with the 80 annular groove 22. The said plug 5 is bored out as shown to form said chamber 6, and in the upper portion of the hollow or enlarged chamber thus produced is fitted the sleeve 23. The said valve member 20 fits the 85 interior bore of the said sleeve 23 as shown, and the said annular groove 22, carried by the valve plug 20, thus forms an annular chamber or passage as illustrated.

The said valve plug 20 is further provided 90 with the inclined or spirally arranged passages 25 which communicate with said annular groove 22 at one end, and at their other end communicate with a similar annular groove 26 which also forms an annular chamber with the interior of said sleeve 23 or with the interior of the hollow plug 14 according to the position in which said valve plug finds itself. The said sleeve 23 is provided with a plurality of radially disposed 95 ports 28 which communicate with the above mentioned annular chamber 16, and each of said spirally arranged passages 25 also communicates with one of said ports 28 when the valve plug 20 is in a certain position, as 100 will appear more fully below.

Said valve plug is capable of a longitudinal movement with respect to the hollow plug or bushing 14, and said bushing is provided with a suitable stuffing box 30 as illustrated. The longitudinal motion is imparted to said valve plug 20 by means of an ex- 110

tension 31, which passes through the stuffing box 30 and is provided with a collar or other means 32 against which takes the end 33 of a lever 34 pivoted as at 35 and joined as by 5 a means 36 to a moving part of the engine not shown.

As the link or means 36 is moved downwardly or in the direction of the arrow illustrated in Fig. 1, the extension 31 and 10 valve plug 20 will be moved upwardly as seen in said figure, and thus compress the spring 37 carried in the housing or cup 38 resting on the adjustable nuts 39 surrounding said extension 31. Said cup or housing 15 38 conveniently reciprocates in the framework 40 and the upper portion of the spring conveniently rests against the cover member 41 through which the upper end 42 of said extension 30 may pass. It is thus evident 20 that as the link or other means 36 reciprocates the valve plug 20 will be moved upwardly against the compression of the spring 37 and the said spring will return said valve plug to its closed position, so that the said 25 plug will reciprocate in synchronism with the moving part of the engine actuating the link 36.

The plug 20 is shown in its lowest position in Fig. 1 wherein it closes the port 4, 30 and it is shown in its raised or open position in Fig. 3. When the plug is in its closed position, as illustrated, the fluid is forced along the passage 11, it will enter the annular chamber 12, the tangential passages 7, the chamber 6, and the port 4 being closed 35 it will next enter the groove 22, the spirally arranged passages 25, the groove 26, the ports 28, the annular chamber 16, and the exit passage 15, all as will be clear from the 40 drawings. On the other hand, when the valve plug 20 is in its raised position as shown in Fig. 3, the port will be open and fluid entering the tangentially arranged passages 7 and the chamber 6 will pass down 45 through said port 4 into the interior 3 of the cylinder 8.

In such open position of the valve plug 20, its lower cylindrical portion 45 will contact with the interior of the sleeve 23 and 50 thus cut off communication between the chamber 6 and the said annular groove 22 so that fluid will no longer be able to enter the passages 25 nor to pass out through the exit passage 15, all as will appear more fully 55 below.

50 represents a fluid supply or inlet pipe joined to the nozzle member 10, as illustrated, and which communicates with the inlet passage 11 as shown. 51 represents an 60 exit pipe also joined to said nozzle 10 and communicating with the exit passage 15 as shown. Joined to the exit pipe 51, is a return pipe 52 provided with an adjustable valve 53 of any suitable construction. 54 65 represents any suitable circulating pump to

which leads the return pipe 52, and to which is joined the inlet pipe 50. Located in the inlet pipe 50 is any suitable heating coil 55. 56 represents a connection with the pipe 52, 70 57 an adjustable valve, 58 a connection between said valve 57 and a feed pump 59, and 60 a connection between said pump 59 and a fuel supply 61.

The operation of the invention, so far disclosed, may be briefly summarized as follows:—

The circulating pump 54 being in operation, fuel such as oil, gas, or other fluids will be circulated through the heating coil 55, the inlet pipe 50, the inlet passage 11, 80 the annular chamber 12, tangential passages 7, the chamber 6, and said valve 20 being closed, said fuel will pass from said chamber 6 into the groove 22, the passages 25, into the groove 26, through the ports 28, 85 through the annular chamber 16, through the exit passage 15, the exit or return pipes 51 and 52 and back to the pump. The passages 7 being tangentially arranged with respect to the chamber 6, as clearly shown 90 in Fig. 6, the said fuel will be given a rotary motion in said chamber 6, the velocity of which will depend upon the difference in pressure of the fluid in the chambers 12 and 6, and upon the area of the said passages 7. 95

That is to say, if the passages 7 are made much smaller in cross sectional area than are the exit passages from the chamber 6 or the inlet passages to the chamber 12, then the speed of the fuel will be greatly increased, 100 and therefore, the velocity of said fuel in the chamber 6 will also be greatly increased. So long as the fuel thus circulates in a closed system, such as is illustrated in Fig. 7, the valve 57 will remain closed and the said 105 pump 59 will not be called upon to supply any additional fuel to the system. On the other hand, when the valve 20 is raised, in the manner above disclosed, and the exit passage 15 is cut off, the fuel will pass down 110 through the port 4 into the space 3 of the engine cylinder 8 and this passage of the fuel into said cylinder will occur even though the said space 3 may be filled full of gas under considerable pressure from the 115 engine piston not shown. In other words, as is well known, prior to my invention, it has been proposed to forcibly inject fuel from a state of rest into an engine cylinder filled with gas under pressure, but it has 120 been invariably found that as soon as a valve such as 20 lifts in such cases, the first portions of the fuel which pass said valve and enter the port 4 must of necessity have a very small velocity, and therefore their 125 speed is not sufficient to cause the individual particles of the fluid to break up into a very fine state of subdivision. Other or following portions of this said fuel, however, attain higher and higher velocities so that the 130

last portions of the charge may mix fairly well with the gases under pressure in the space 3.

But, on the other hand, the fact remains 5 that in said prior devices it has not been heretofore possible to impart a sufficient velocity to those portions of fuel which initially enter the cylinder to cause them to finely subdivide, and therefore, the injection 10 of fuel against gases under pressure in cylinders by the older devices has not been satisfactory.

By following the process above disclosed, however, the particles of fuel at all times 15 may have a very high velocity, and therefore, as soon as the valve 20 lifts, the initial as well as the oncoming particles enter the space 3 filled with gas under pressure at a very high velocity, they are each and all 20 possessed of a great deal of momentum, and consequently, they suffer a very fine subdivision, and therefore, they mix thoroughly with said compressed gas throughout the period of injection.

25 It results from this that the subdivision and the mixing of a charge of fuel injected into a combustion chamber according to my process is much more perfect and the explosion and combustion is much more rapid 30 and perfect than it is possible to attain under the old system.

Further, by suitably adjusting the valve 35 53 and the static or dead pressure in pipe 50, the static or dead pressure in the pipe 51, and in the chamber 6 may be made to have any value desired, while by providing a suitable speed for the pump 54, the velocity 40 of the fuel in said chamber may also be made to have any value desired. In other words, by employing the closed system, above illustrated, fuel in the chamber 6 may not only be given a very high velocity, but it may also, at the same time, be maintained in said chamber at a pressure higher than the pressure 45 in the space 3. It results from this that I am enabled to successfully use fuels of a higher viscosity than heretofore, to attain a better mixing effect in the space 3 of the cylinder, and to prevent the compressed 50 gases in the space 3 from entering the pipes 50 and 51, a combined result not heretofore possible, so far as I am aware.

As the fuel is injected into the cylinder 8, the pressure in the pipe 52 is reduced, and 55 the valve 57 having been set at the proper point will lift, whereupon the pump 59 automatically supplies a sufficient amount of fuel to replace the fuel lost from the closed system, and maintains the pressure that has 60 been previously fixed in the pipe 52 by the adjustment of the valve 57.

In addition to the above, by passing the fuel through the heating coil 55 before it reaches the chamber 6, I am enabled to impart 65 any desired temperature to said fuel

before igniting it in the cylinder. By thus preheating the fuel before it is injected into the cylinder, ignition is rendered more easy, and certain and the smooth operation of the engine is insured.

In the form of the invention shown in Figs. 8 and 9, instead of providing for a rotary motion of the fuel before it reaches the port 4, the fuel is merely forced through the inlet 60, and passages 61 of the valve 62 to the annular chamber 63 whence it passes out through the exit 64 if the valve 65 be closed, or it passes down through the port 4 if said valve 65 is open. In this case 70 it will be seen that a continuous motion 80 is also imparted to the fuel by means of the pump 54 through the pipes 50 and 52. 66 represents a fuel supply and the valve 65 may be operated by any suitable means not shown.

In the still further modified form of the invention shown in Fig. 2, 70 represents a combustion flask such for example as a turbine chamber, 71, 72 and 73 injectors of the types above disclosed each associated with 90 closed circuits not illustrated, but each capable of delivering a fluid to its corresponding injector, and there imparting to said fluid a predetermined continuous velocity. For example, injector 71 may deliver a hydrocarbon oil, injector 72 may deliver air, or oxygen, and injector 73 may deliver water, their location being so arranged that an intimate mixture of the sprays from injectors 71 and 72 takes place for combustion or explosion, 100 and the spray from injector 73 being arranged to cool or be heated from the products of combustion. The final gaseous mixture escapes through the directing nozzle 75 against the buckets 76 of a turbine wheel.

In all the forms of the invention it will be seen that I have provided a method of and apparatus for injecting fuel, whether liquid or gaseous or a mixture of the two, or a mixture of one or both with finely divided 110 solids, into an engine cylinder or combustion chamber. That in each form I impart to said fuel a continuous motion, by virtue of which the fuel is injected into and mixed with the contents of the combustion chamber. By this mode of procedure it will be clear that I am enabled to cause the very first or initial portions of the fuel entering said chamber containing compressed gases therein to finely subdivide and to mix with said compressed gases just as efficiently as do the last portions of each charge, a result not heretofore attained, in so far as I am aware. Further, it will be observed that I am enabled to regulate the constant continuous 120 or static pressure existing in the closed circuits so that said compressed gases in said combustion chamber do not leak out into the fuel circuit.

It will also be observed that I am enabled 130

to regulate the velocities at which the fuel or other fluids pass the port 4, and therefore I can successfully use in the engine at different times fuels of different qualities.

5 In practice I prefer to so control the movements of the valve 20 as will permit some passage of the fuel or fluid through the system at all times. It is evident that the quantity of fuel or fluid admitted to the 10 combustion chamber may be readily varied by varying the duration of the period between the opening and closing of the port 4, and thus eliminate the necessity of employing the devices for measuring the quantity 15 of fluid or fuel that are now ordinarily employed.

It is further evident that when a plurality of injectors are employed on the same cylinder, or combustion chamber, (see for example Fig. 2), each of said injectors may independently control the admission of a separate fluid such as a fuel hydrocarbon, air and water, and thus greatly improve the control of the combustion in the cylinder, 25 and the efficiency of the engine.

It will also now be clear that an important feature of this invention is to be found in the fact that I am enabled to eliminate all 30 atomizing or spraying agents such as compressed air, and their accompanying complicated apparatus, as well as their attendant objections. Where the engine is of small horse power and only a very small quantity 35 of fuel is injected at a time, into the cylinder, I prefer to so control the movements of the valve 20 as will permit the passage of the major portion of the fuel, or fluid, through the system at all times, in order to better control the quantity and velocity of 40 the fuel injected.

It will be observed that by the continuous circulation of oil around the valve stem the latter is kept cool, provided the oil itself is cool, but of course, the heat acquired by the 45 oil gradually raises its temperature. Should this heat become excessive from any cause, I may readily reduce the temperature at any time by employing the coil 55 as a cooling coil instead of a heating coil. In fact, should 50 there develop any tendency of the oil to decompose with a consequent deposit of carbon, I could employ the said coil 55 as a cooling coil, or in some cases, I could employ two coils in the circuits 50 and 52, the 55 one for heating the oil and the other for cooling the same. While one coil is being employed the other may be cut off. In addition to the above, should carbon or other foreign matter appear in the oil it will be 60 then desirable to employ a filter in the circuit. Such filter may be of any desired construction and placed at any convenient portion of the circuit.

It is obvious that those skilled in the art 65 may vary the steps and combinations of

steps constituting my process as well as the details of the construction and the arrangement of parts constituting the apparatus, without departing from the spirit of the invention, and therefore, I do not wish to be limited to the above disclosure except as may be required by the claims.

What I claim is:—

1. The process of injecting fuel into a combustion chamber which consists in imparting a continuous motion under pressure to said fuel; increasing the velocity of said fuel at a point in its path; and automatically at said point admitting a portion of the moving fuel into said combustion chamber, substantially as described. 75

2. The process of injecting fuel into an engine cylinder containing a gas under pressure, which consists in imparting a continuous and uninterrupted motion to said fuel sufficient to enable it to overcome the resistance of said gas; and intermittently admitting the moving fuel into said cylinder, substantially as described. 85

3. The process of injecting fuel into an engine cylinder against the resistance of a compressed gas therein, which consists in imparting a continuous rotary motion to said fuel sufficient to overcome said resistance; and intermittently admitting said rotating fuel into said cylinder, substantially as described. 91

4. The process of injecting a fuel into an engine cylinder which consists in imparting a continuous predetermined velocity and pressure to said fuel outside said cylinder; and automatically at predetermined intervals opening communication between said fuel and said cylinder, substantially as described. 11

5. The process of injecting fuel into an engine cylinder containing a gas under pressure, which consists in preheating said fuel; imparting a continuous motion in a closed circuit to said preheated fuel sufficient to enable it to overcome the resistance of said gas; and intermittently admitting the moving fuel into said cylinder, substantially as described. 1

6. In an apparatus for injecting fuel into an engine cylinder, the combination of means for imparting a predetermined continuous rotary motion to said fuel outside said cylinder; and means for automatically and intermittently admitting said fuel to said cylinder, substantially as described. 1

7. In an apparatus for injecting fuel into an engine cylinder the combination of a fuel supply; means for imparting a continuous rotary motion in a closed circuit to said fuel outside said cylinder; means for preheating said fuel; and means for automatically and intermittently admitting said preheated fuel into said cylinder, substantially as described. 1

8. In an apparatus for injecting fuel into

an engine cylinder, the combination of a pump and connections for continuously circulating the fuel in a closed system; an injector nozzle in said system connected to said cylinder; a valve controlling communication between said nozzle and cylinder; and means associated with said nozzle for increasing the velocity of said fuel as it moves past said valve, substantially as described.

10. 9. In an apparatus for injecting fuel into an engine cylinder, the combination of a pump and connections for continuously circulating the fuel in a closed system; an injector nozzle in said system connected to said cylinder; a valve controlling communication between said nozzle and cylinder; and means associated with said nozzle for imparting a rotary motion to, and increasing the velocity of said fuel as it moves past said valve, substantially as described.

15. 10. In an apparatus for injecting fuel into an engine cylinder the combination of an injector nozzle provided with a port entering said cylinder; a valve controlling said port; means for automatically operating said valve; and means for continuously imparting a rotary motion at a high velocity to said fuel as it passes said valve, substantially as described.

20. 11. In an apparatus for injecting fuel into an engine cylinder the combination of an injector nozzle provided with a port entering said cylinder; a valve controlling said port; means for automatically operating said valve; means for preheating said fuel; means for controlling the pressure of said fuel at said valve; and means for continuously imparting a rotary motion at a high 25 velocity to said fuel as it passes said valve, substantially as described.

25. 12. In an apparatus for injecting fuel into an engine cylinder the combination of an injector nozzle provided with a port entering said cylinder; a valve controlling said port; means for automatically operating said valve; means for preheating said fuel; means for supplying fuel to the system as fast as it is taken therefrom; and means 30 for continuously imparting a rotary motion

at a high velocity to said fuel as it passes said valve, substantially as described.

13. The process of injecting a fuel and a fluid into a combustion chamber which consists in imparting continuous motions to said fuel and fluid; and automatically independently and intermittently admitting the moving fuel and fluid into said chamber, substantially as described.

14. The process of injecting a fuel and water into an engine cylinder which consists in imparting continuous motions to said fuel and water; and automatically, independently, intermittently and successively admitting the moving fuel and water into said cylinder, substantially as described.

15. The process of injecting a fluid into an inclosure which consists in continuously circulating said fluid along a predetermined path and at a predetermined point not located at the end of said path imparting a rotary motion to said fluid; and admitting a predetermined portion of the same into said inclosure, substantially as described.

16. In an apparatus for injecting fuel into an engine cylinder, the combination of means for continuously circulating the fuel in a closed system, an injector nozzle in said system connected to said cylinder; a valve controlling communication between said nozzle and cylinder, means associated with said nozzle for increasing the velocity of said fuel as it moves past said valve; and means associated with said valve for increasing the pressure of the moving fuel when said valve opens and admits fuel into the engine cylinder, substantially as described.

17. The process of injecting fuel into a combustion chamber which consists in imparting motion and pressure to said fuel; increasing the velocity and decreasing the pressure of said fuel at a predetermined point in its path; and then automatically and intermittently at said point increasing the pressure of said fuel while admitting the same into said chamber, substantially as described.

In testimony whereof I affix my signature.
JOSEPH O. FISHER.
